UNITED STATES PATENT OFFICE.

GUSTAV F. HOCHRIEM, OF CHICAGO, ILLINOIS, ASSIGNOR TO RHODES-HOCHRIEM MANUFACTURING COMPANY, OF CHICAGO, ILLINOIS, A CORPORATION OF ILLINOIS.

DESIGN FOR A HEAD OF A PRINTING SCALE.

Application filed May 13, 1927. Serial No. 21,963. Term of patent 3½ years.

To all whom it may concern:

Be it known that I, GUSTAV F. HOCHRIEM, a citizen of the United States, residing at Chicago, county of Cook, State of Illinois, whose post-office address is No. 150 North Desplaines Street, Chicago, Illinois, have invented a new, original, and ornamental Design for a Head of a Printing Scale, of which the following is a specification, ref-

erence being had to the accompanying drawing, forming part thereof.

Figure 1 is a perspective view of the head showing my design;

Fig. 2 is a front elevation thereof.

I claim:

The ornamental design for a head of a printing scale, as shown.

GUSTAV F. HOCHRIEM.
